UNITED STATES PATENT OFFICE

ROBERT E. WILSON, OF CHICAGO, ILLINOIS, ASSIGNOR TO STANDARD OIL COMPANY, OF WHITING, INDIANA, A CORPORATION OF INDIANA

ART OF PRESSURE DISTILLATION OF HYDROCARBON OILS

Application filed March 13, 1925. Serial No. 15,258.

The present invention relates to improvements in the art of pressure distillation of heavier hydrocarbon oils for the production of lower boiling point products, such as gasoline. It will be fully understood from the following description, illustrated by the accompanying drawing, in which apparatus for carrying out the invention is diagrammatically shown.

5 In the apparatus illustrated, the numeral 5 indicates a diagrammatic representation of a heating coil installed in a suitable furnace setting 6, and to which oil is supplied by a pump 7, suitably a surge pump, through pipe 8. From the coil 5, the heated oil passes through a line 9 to a drum 10, which may suitably be lagged or otherwise arranged to conserve the heat of the oil supplied thereto. Within the drum 10 there are provided one or 15 more vertical partition walls or baffles 11 extending from near the bottom of the shell upwardly, and dividing the fluid contents of the still into segregated pools 12, 13 and 13^a which communicate with one another by flow through openings 11^a in the lower portions of the baffles 11. The vapor spaces of the several pools communicate above the baffles. From the pool 12, into which the oil from the heating coil 5 is discharged, a return or circulating pipe 14, controlled by valve 15 leads to a small chamber 27 which communicates with the intake of pump 7 through pipe 29. From the pool 13^a a draw-off line 16, controlled by valve 17, is provided 20 for the discharge of unvaporized oil.

25 Vapors evolved from the oil in the several pools 12, 13 and 13^a, and collecting in the vapor space above their liquid contents, pass out through vapor line 18 into the lower portion of a tower 19 mounted on a suitable setting 30. In the tower 19, the vapors are cooled to condense therefrom the liquid vaporized products heavier than the light boiling products desired. This cooling may be effected by any desired means, such as direct radiation from the upper part of the shell of the tower, or by supplying to the top plate of the tower, suitably through pipe 21, a suitable medium, such as distillate product, raw oil of the nature of the original stock treated,

or special feed stocks. Uncondensed products pass out of the dephlegmator through vapor line 20 to any suitable condensing apparatus, preferably maintained under pressure.

Reflux condensed in the tower, together with the unvaporized portions (if any) of the stock fed into the tower through the line 21, passes out of the bottom of the dephlegmator through line 22. The reflux is then 55 preferably conducted to the chamber 27 through line 23, controlled by valve 24. Optionally, the reflux passing out through line 22 may be caused to pass, in part or wholly, through line 25, controlled by valve 26 and be discharged into the body of oil 60 within the pool 12 or other suitable pools in the chamber 10.

Fresh oil to be treated may be fed under pressure to the intake side of the pump 70 through the line 28, controlled by valve 28.

In the operation of the present process, fresh oil is suitably introduced under pressure through the valved line 28 into chamber 27, from which the pump forces it 75 through the coil 5, in which it is heated to cracking temperature. The heated oil then passes into the pool 12 in the shell 10, preferably first passing through coils 9^a in pools 13 and 13^a and caused to flow slowly from pool 12 through openings 11^a into pools 13 and 13^a, 80 which are gradually filled. The oil is retained in the pools 12, 13 and 13^a, in which it is maintained at a conversion temperature, the temperature and rate of flow being controlled with respect to one another to cause 85 an adequate conversion into light products of the desired character (such as gasoline). After the pools 12, 13 and 13^a have been sufficiently filled with heated oil, the valve 15 is opened, and oil from the pool 12 is withdrawn through the line 14 to chamber 27 and circulated by pump 7 through the heating coil 5. The proportion of oil re-circulated may be readily determined by the setting of the valve 15, and may suitably 90 be from 15 to 40% of the amount of stock pumped through the coil.

The oil flowing from the pool 12 into the pools 13 and 13^a is subjected therein to an 95 additional substantial conversion, and un-

converted oil is withdrawn through the pipe 16, its proportion being controlled by the valve 17. Vapors arising from both pools pass into the fractionating tower 19. Atmospheric radiation may be used to cause fractionation of the vapors, returning substantially all the vapors heavier or of higher boiling point than the desired products. If atmospheric radiation is insufficient, or a more effective control of the cooling in the tower is desired, oil of approximately the same characteristics as the final distillate may be fed into the tower through the pipe 21 in any desired proportions, cooling the tower and, itself being vaporized and passing off with the uncondensed vapors through the line 20. In some cases it is found preferable to supply raw oil to be cracked into the tower through the line 21, the oil thus supplied being preheated in the tower and passing off with the reflux as hereinafter described.

The reflux condensed in the tower 19 may be conducted by the lines 22 and 23 to the chamber 27, and being then forced by pump 7 through the heating coil 5 with the circulated oil supplied to the chamber 27 through the line 14 and such fresh oil as may be supplied through the line 28. If it is not desired to return the reflux to the system through the heating coils, it may be returned directly to the pool 12 through the line 25, mingling there with the heated oil supplied from the coil 5. As is readily apparent the valves 24 and 26 may be manipulated to control the flow of the reflux. When raw oil is fed through the pipe 21 into the dephlegmator, the supply of fresh oil through the line 28 may be correspondingly diminished or cut off.

The entire apparatus is preferably maintained under superatmospheric pressure, say a pressure in excess of 4 atmospheres. The oil, in passing through the coil 5, is heated to a conversion temperature, and preferably to a temperature of 750 to 850° F., at which temperature it enters the pool 12. The still 10 is lagged or thermally insulated or may be very moderately heated, so that the oil may be retained therein for a substantial period of time at conversion temperature; in general, the drop in temperature should not be more than 75° below the entrance temperature of the heated oil. The flow of oil through the line 14 back to the heating zone and the discharge through line 16 are so controlled that not more than 25% and preferably 10 to 15% of products boiling within the boiling range of gasoline are removed therefrom in pool 12.

I claim:

1. In the pressure distillation of oils heavier than gasoline for the production of a gasoline-like products, forcing oil through a heating zone into a maintained pool, thereby

bringing the oil to conversion temperature, discharging liquid products from said pool to another pool, removing oil continuously from the later pool, the oil passing from the heating zone to the first pool being led in a confined stream through the later pool in indirect heat conductive relationship with the liquid contents thereof, and forcing oil from the initial pool through the heating zone to said initial pool.

2. In the pressure distillation of oils heavier than gasoline for the production of gasoline-like products, circulating oil from a maintained pool to and through a heating zone, discharging liquid products from said pool to another pool, both said pools being maintained at conversion temperature, solely by the heat imparted to the oil circulated through the heating zone removing oil continuously from the later pool, feeding raw oil through the heating zone to the first pool, and converting from 10 to 15% of the oil fed to said first pool to gasoline-like products before leaving said pool.

3. In the pressure distillation of oils heavier than gasoline for the production of gasoline-like products, maintaining a plurality of bodies of oil and causing oil to flow successively therethrough, withdrawing oil from the first of said oil bodies, passing it together with fresh oil through a heating zone maintained at a cracking temperature, and returning it in heated state to said first oil body after first passing it in heat conductive contact with the liquid contents of a later oil body, thereby maintaining all said oil bodies at cracking temperature.

4. In the pressure distillation of oils heavier than gasoline for the production of gasoline-like products, maintaining a plurality of bodies of oil and causing oil to flow successively therethrough, withdrawing oil from the first of said oil bodies, passing it through a heating zone maintained at a cracking temperature, returning it in heated state to said first oil body after first passing it in heat conductive contact with the liquid contents of a later oil body, thereby maintaining all said oil bodies at cracking temperature, withdrawing evolved vapors from at least one of said oil bodies and cooling said vapors to condense therefrom products heavier than the desired gasoline-like products, and passing the said condensate to the oil undergoing cracking.

5. In the pressure distillation of oils heavier than gasoline for the production of gasoline-like products, maintaining a plurality of bodies of oil and causing oil to flow successively therethrough, withdrawing oil from the first of said oil bodies, passing it through a heating zone maintained at a cracking temperature, returning it in heated state to said first oil body after first passing it in heat conductive contact with the liquid contents

of a later oil body, thereby maintaining all said oil bodies at cracking temperature, withdrawing evolved vapors from at least one of said oil bodies and cooling said vapors to condense therefrom products heavier than the desired gasoline-like products, and passing the said condensate together with fresh oil to the oil undergoing cracking.

6. In the pressure distillation of oils heavier than gasoline for the production of gasoline-like products, maintaining a plurality of bodies of oil and causing oil to flow successively therethrough, withdrawing oil from the first of said oil bodies, passing it through a heating zone maintained at a cracking temperature, returning it in heated state to said first oil body after first passing it in heat conductive contact with the liquid contents of a later oil body, thereby maintaining all said oil bodies at cracking temperature, withdrawing evolved vapors from at least one of said oil bodies and cooling said vapors to condense therefrom products heavier than the desired gasoline-like products, and passing the said condensate through said heating zone.

7. In the pressure distillation of oils heavier than gasoline for the production of gasoline-like products, maintaining a plurality of bodies of oil and causing oil to flow successively therethrough, withdrawing oil from the first of said oil bodies, passing it through a heating zone maintained at a cracking temperature, returning it in heated state to said first oil body after first passing it in heat conductive contact with the liquid contents of a later oil body, thereby maintaining all said oil bodies at cracking temperature, withdrawing evolved vapors from at least one of said oil bodies and cooling said vapors to condense therefrom products heavier than the desired gasoline-like products, and passing the said condensate together with fresh oil through said heating zone.
